COMBINED CONDENSER AND RESISTANCE UNIT

Application filed March 8, 1924. Serial No. 697,724.

This invention relates to a combination condenser and resistance unit which is particularly adapted for use in connection with radio circuits. In certain of these radio circuits a condenser shunted by resistance is used in connection with the grid circuit, the resistance being commonly referred to as a "grid leak".

In order to simplify the wiring of a radio set of this character, I have combined the two pieces of apparatus into one unitary structure, which in the drawings attached to this specification, is shown in Figure 1, the view being taken at somewhat of an angle in order 15 to show clearly the arrangement of the combination structure.

Figure 2 is an end view of the combined device; while

Figure 3 is a bottom view.

In the different views, like numbers refer 20 to corresponding parts. 1 represents a body of a condenser built up in the wellknown manner using alternative layers of tinfoil and a suitable dielectric, such as paper or 25 mica, the edges of the foil extending beyond the sides and being bent over, the pile being held together by flat binding plate members of suitable insulating material engaged by the 30 clamping members 2 and 3, which also make contact with the opposite conducting elements, as described in Van Deventer Patent 1,181,623. The clamping members have a 35 number of clips 4 punched outwardly from the metal. Certain of these clips, such as shown in Fig. 1, enter holes or recesses 5 in the outside binding members and are bent over so as to prevent the clamping members 2 and 3 from being pulled off the condensed 40 pile and out of contact with the conducting elements. It is to be understood that the 45 clips which are bent downward into the holes or recesses 5 are preferably shorter than the thickness of the binding members so that there is no danger of these particular clips 50 engaging the metallic foils on the outer layers of the condenser stack. The clips 4 on the bottom side of the clamping member 2 and 3 are used to grip auxiliary terminals 6 and 7, which are preferably made of spring or 55 resiliency material and are provided with holes

through which two sets of the clips 4 pass, these clips being bent over as indicated at 8. I prefer to throw these clips downward on both ends of the clamping members 2 and 3, as indicated in Fig. 3 in order that the same 60 clamp may be used for both sides of the condenser. Members 2 and 3 are provided with clamping lugs 9, each having a hole 10 therein for mounting the condenser unit. As will be seen from Fig. 1, the lugs 9 are punched 65 outwardly from the body of the clamping members. The terminals 6 and 7 are bent at an angle as clearly shown in the drawings and pass upward along the sides of the condenser to a little distance above the surface or top 70 portion of the condenser. Each of these clips is provided with an orifice 11 and between the clips is adapted to be positioned a resistance unit usually made up of resistance inside a glass tube 12 having metal terminals 13 thereon. The terminals 13 are adapted to enter the 75 orifices 11 thereby holding the resistance unit securely in position between the auxiliary terminals 7 and 8.

A very important feature of my invention 80 is the connector projections 14 which extend outwardly from the lugs 9. These projections 14 may have small holes in them for the reception of wires if necessary, although I have found that wires may be soldered directly to the projections 14 without these 85 projections being formed in any special manner or provided with any orifice. The object of these projections is so that in soldering the connecting wires thereto, the heat will be dissipated before it is conducted through 90 the clamping members to the conductor elements of the condenser. It will be understood that the capacity of radio condensers of this kind is very low, many of them being built of only two conductor sheets with a dielectric therebetween. These conductor sheets are very thin and any amount of heat would either melt or injure them to such an extent as to render the condenser defective, but by reducing the amount of metal 95 to be heated and placing this metal at a considerable distance from the conductor elements, I have effected a decided improvement in the construction of such condensers. 100

It will be understood that my invention is susceptible to reasonable modifications without departing from the spirit of the same and the scope of the appended claim.

Having thus described my invention, what I claim is:

In a device of the class described, a condenser having clamping members on opposite sides thereof and in electrical engagement with the opposite conducting condenser elements thereby forming terminals, said clamping members having integral clips for engaging a part of the body of the condenser to hold the clamping members in operative position and also having integral mounting lugs and connector projections extending outwardly from said lugs, said projections being so small that they will become heated sufficiently to perform a soldering operation long before the lugs reach such soldering temperature.

In testimony whereof, I affix my signature.

EDWARD B. NOWOSIELSKI.
